DESIGN FOR A COMBINED DISPLAY CASE AND PEN DEMONSTRATOR UNIT

Paul M. Ressinger, Chicago, Ill.

Application November 14, 1941, Serial No. 164,150

Term of patent 14 years

To all whom it may concern:

Be it known that I, Paul M. Ressinger, a citizen of the United States, residing at Chicago, in the county of Cook and State of Illinois, have invented a new, original, and ornamental Design for a Combined Display Case and Pen Demonstrator Unit, of which the following is a specification, reference being had to the accompanying drawing, forming part thereof.

Fig. 1 is a front perspective view of a combined display case and pen demonstrator unit, showing my design;

Fig. 2 is an end elevational view; and
Fig. 3 is a top plan view thereof.

I claim:

The ornamental design for a combined display case and pen demonstrator unit, as shown.

PAUL M. RESSINGER.
